UNITED STATES PATENT OFFICE.

JOSEPH YOST, OF NEW YORK, N. Y.

DESIGN FOR A TOY WHISTLE.

Application filed December 9, 1922. Serial No. 4,537. Term of patent 3½ years.

To all whom it may concern:

Be it known that I, JOSEPH YOST, a citizen of Germany, residing at New York, in the county of New York and State of New York, have invented a new, original, and ornamental Design for Toy Whistle, of which the following is a specification, reference being had to the accompanying drawing, forming a part thereof.

I claim:

The ornamental design for toy whistle as shown.

JOSEPH YOST.
